CLAIM

The ornamental design for a fire extinguisher stand, as shown and described.

DESCRIPTION

FIG. 1 is a perspective view of the present invention;

FIG. 2 is a right side elevation view thereof;

FIG. 3 is a left side elevation view thereof;

FIG. 4 is a front side elevation view thereof;

FIG. 5 is a back side elevation view thereof;

FIG. 6 is a top plan view thereof;

FIG. 7 is a bottom plan view thereof; and,

FIG. 8 is a partial section, perspective view thereof, from the same perspective as that of FIG. 1.

Any broken lines shown in the figures depict portions of the fire extinguisher stand and form no part of the claimed design.
